Jan. 8, 1963

P. YAFFEE

3,072,904

CONTROL APPARATUS FOR TRANSMITTING STATION

Original Filed Nov. 4, 1955

INVENTOR.
P. YAFFEE

BY

*W. Quesenberry
D. Hodges*

ATTYS.

oscillator and to the local oscillator of said receiver for developing an output difference frequency signal, and an amplifier circuit coupled to said mixer circuit for terminating operation of said tuning means in response to an output difference signal of a preselected frequency indicative of a transmitter transmitting frequency commensurate with said predetermined frequency and the intermediate frequency of said receiver.

References Cited in the file of this patent

UNITED STATES PATENTS

2,415,874	Goldstine	Feb. 18, 1947
2,640,150	Wu	May 26, 1953
2,643,329	Silver	June 23, 1953
2,648,063	Schmitt	Aug. 4, 1953
2,820,889	Overacker	Jan. 21, 1958